Primary Examiner — Catherine Tuttle(74) *Attorney, Agent, or Firm* — Thomas I. Rozsa(57) **CLAIM**

The ornamental design for a square-shaped double bottle formed from two triangular bottles retained together to form a full square-shaped double bottle, as shown and described.

DESCRIPTION

FIG. 1 is a perspective view showing my new design for the square-shaped double bottle formed from two triangular bottles retained together to form a full square-shaped double bottle;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a bottom plan view thereof;

FIG. 7 is a top plan view thereof;

FIG. 8 is a bottom perspective view thereof;

FIG. 9 is a perspective view showing the rear triangular bottle separately for clarity and to disclose the surface obscured in the assembled views;

FIG. 10 is a front elevational view thereof;

FIG. 11 is a rear elevational view thereof;

FIG. 12 is a left side elevational view thereof;

FIG. 13 is a right side elevational view thereof;

FIG. 14 is a bottom plan view thereof;

FIG. 15 is a top plan view thereof; and,

FIG. 16 is a bottom perspective view thereof.
